[57] **CLAIM**

The ornamental design for joint for the frame of a rolling cart, as shown and described.

DESCRIPTION

FIG. 1 is a perspective view of a joint for the frame of a rolling cart showing our new design;
FIG. 2 is a front elevational view thereof;
FIG. 3 is a rear elevational view thereof;
FIG. 4 is a top plan view thereof;
FIG. 5 is a bottom end view thereof;
FIG. 6 is a left side elevational view thereof;
FIG. 7 is a right side elevational view thereof;
FIG. 8 is a sectional view along line 8—8 of FIG. 2;
FIG. 9 is a sectional view along line 9—9 of FIG. 7; and,
FIG. 10 is a perspective view showing the use of a joint for the frame of a rolling cart fitting to the frame member. The broken lines are for illustrative purposes only and form no part of the claimed design.
